2,051,001

LOCOMOTIVE

Paul A. Ketchpel, West Englewood, N. J., assignor to The Standard Stoker Company, Incorporated, a corporation of Delaware

Application May 4, 1932, Serial No. 609,088

13 Claims. (Cl. 110—120)

This invention relates to locomotives and has particular reference to novel means for recapturing unconsumed fuel particles and reintroducing them into the locomotive firebox.

5 The principal object of my invention resides in the provision of apparatus for the recovery of unconsumed fuel particles and for their reintroduction into the locomotive firebox in a manner to insure their complete combustion, thereby eliminating the recirculation of the reintroduced fuel particles and insuring a maximum amount of heat with a minimum expenditure of fuel.

To this end my invention consists in the provision, in a locomotive, of means whereby unconsumed or partially consumed fuel particles escaping from the firebox are separated from the gaseous products of combustion, and of a conveying system including a pulverizing unit whereby the separated particles are returned and discharged into the forward end of the locomotive firebox in a comminuted state effecting complete combustion thereof in suspension.

It further consists in the provision, in a stoker equipped locomotive, of apparatus of the type described in which the pulverizer is mounted on the locomotive frame beneath the cab deck, the pulverizer and stoker being operated in timed relation from the same prime mover, and the comminuted fuel is discharged into the firebox through its rear wall beneath the stoker fired fuel.

Another object of the invention resides in the provision of a novel form of locomotive cylinder saddle casting having formed therein a trough arranged to form the bottom of a smokebox.

35 Other and further objects and advantages of the invention reside in the details of construction of the constituent elements and the combination and arrangement of parts, as will become apparent from the appended description and claims 40 and as illustrated in the drawings, in which

Figure 1 is a side elevation of a locomotive with the preferred form of the invention properly applied, parts of the locomotive being broken away and parts shown in section to more clearly illustrate the invention;

Figure 2 is a sectional view on the line 2—2 of Figure 1 with parts broken away;

Figure 3 is a fragmentary sectional plan view on the line 3—3 of Figure 1;

50 Figure 4 is a side elevation of the rearward portion of the locomotive with parts broken away and parts shown in section, showing a modified form of the invention applied thereto; and

Figure 5 is a rear elevation of the locomotive with the modified form of the invention applied,

parts being broken away and parts being shown in section.

For purposes of best illustrating the preferred embodiment of the invention, it will be described with particular reference to its application with a 5 locomotive boiler furnace. However, it will become obvious as the description proceeds that the invention may advantageously be applied to other types of boiler furnaces in which the amount of unconsumed fuel particles is sufficient 10 to warrant the recovery thereof.

Referring now to the drawings, in particular to Figures 1, 2 and 3, the locomotive boiler 10 is traversed by a plurality of fire tubes or flues 11, extending from the firebox 12 to the smokebox 13. 15 At its forward end, the smokebox 13 is closed by a forward wall 14 having a door 15 closing an opening in the forward wall 14 through which access is afforded to the interior of the smokebox 13, for the insertion and removal of members 20 contained therein.

The smokebox 13 is supported on the cylinder saddle casting 16 in the customary manner, the cylinders 17 being preferably, though not necessarily, formed integral with the saddle casting 16. 25 The smokebox 13 is divided into the compartments 18 and 19 by a diaphragm or wall that comprises a rear imperforate portion 20, and a foraminous portion or screen 21. The compartment 19 communicates directly with the flues 11 30 and the compartment 18 communicates directly with the inside stack or petticoat pipe 22 and the smoke stack 23, through which the waste gases of combustion are discharged to the atmosphere.

The waste gases of combustion carry a relatively 35 large amount of cinders and unconsumed fuel particles which pass over the firebox arch 24, through the flues 11 into the chamber 19. The foraminous wall portion or screen 21 permits the waste gases of combustion to pass therethrough 40 into the chamber 18 and then out the stack 23, and retains the solid particles. The separated solid particles drop from the screen 21 onto a chute or wall 25 that extends downwardly and rearwardly from the forward wall 14 of the smokebox and are deposited in the lower forward portion of the smokebox. 45

Located in the smokebox and below the petticoat pipe 22 is an exhaust steam pipe 26 arranged, conventionally or otherwise, in communication 50 with the exhaust cavities 27 in the saddle casting 16 of the locomotive piston cylinders 17. The saddle casting 16 is provided with a longitudinally extending depression forming a V-shaped trough 28 which forms a bottom for the smokebox. By 55

forming the floor of the smokebox in this manner, the deposited cinders and unconsumed fuel particles are concentrated in a narrow channel from which they may be conveniently removed 5 in a suitable manner. At the same time, the trough-like smokebox floor being formed in the saddle casting occupies space which could otherwise not be used for any purpose.

Preferably, the deposited solid particles are 10 discharged from the smokebox through the rearward lower end thereof by a pressure fluid blast issuing from a nozzle 29 located at the forward lower end of the smokebox in the trough 28. To prevent the dissipation of the pressure fluid blast 15 throughout the smokebox, a tubular member 30 is disposed longitudinally in the trough 28. The tubular member 30 is provided at its opposite ends with the openings 31 and 32 through which the deposited solid particles pass into the path 20 of the pressure fluid blast in the trough 28. To prevent the collection of fuel particles on the tubular member 30, the trough is provided with a transversely extending ridge formed by the oppositely sloping plate members 33 and 34, thereby 25 making the smokebox self cleaning.

A conduit 35, communicating with the rearward end of the tubular member 30, extends rearwardly from the lower end of the smokebox 13 beneath the boiler 10 towards the firebox 12. At 30 its rearward end, the conduit 35 communicates with a casing or settling chamber 36, which is mounted adjacent the outside sheet of the front water leg 37 of the boiler 10. The settling chamber 36 is divided into chambers 38 and 39 by a 35 screen 40. Cinders and unconsumed fuel particles discharged from the smokebox by the blast issuing from the nozzle 29 pass through the conduit 35 and into the casing or settling chamber 36. The carrier fluid passes through the screen 40 into the chamber 39 and is discharged through the pipe 41 into the smoke stack 23.

The solid particles separated by the screen 40 drop through an opening 42 in the bottom of the settling chamber 36 into a pulverizing unit 43. The pulverizing unit, comprising a pulverizer 44 and a fan 45, may be of any desired form, which will effectively reduce the solid particles to the necessary fineness and produce a blast for blowing it into the firebox. The fan 45 ejects 45 the fine material through a nipple 46 to which is attached a delivery nozzle 47 projecting into the firebox 12 through an opening 48 in the front leg 37 of the boiler 10. The motor for the pulverizing unit 43 is preferably a turbine and is 50 conventionally shown at 49.

In operation, coal is delivered to the firebox 12 through the conventional firing opening 50 by manual firing or as illustrated, by a stoker indicated generally at 51. The waste gases of combustion pass over the arch 24 into the flues and carry with them relatively large quantities, ranging from about 11% to 40%, of solid materials including cinders and unconsumed fuel particles. From the flues the products of combustion of the 55 firebox pass into the smokebox 13, where the solid particles are separated from the waste gases of combustion by the screen 21, the gases escaping through the stack 23 and the solid particles dropping by gravity into the trough 28 in the 60 path of the blast issuing from the nozzle 29. The blast projects the solid particles through the rearwardly extending conduit 35 into the settling chamber 36, where the carrier fluid is separated 65 from the solid particles and suitably vented, the 70 solid particles dropping by gravity into a pul- 75

verizer 44. The pulverized material is ejected into the firebox by the fan 45, and is commingled with sufficient air to insure its perfect combustion in the firebox while in a state of suspension. In this manner, there is effected not only a saving 5 in fuel consumption, but also recirculation of the cinders and unconsumed fuel particles through the flues is eliminated, as would result if the solid particles were reintroduced into the firebox above the firebed without preliminary pulveriza- 10 tion.

In Figures 4 and 5 is shown a modified form of the invention. The front end arrangement, since it is similar to the arrangement of the preferred embodiment has not been shown in these figures 15 nor will it be necessary to again describe it. The rear or firebox arrangement provides a settling chamber 52 and a pulverizing unit 53 mounted on the locomotive frame 54 beneath the locomotive cab deck 55. As in the preferred form of 20 the invention fuel is delivered to the firebox through the firing opening 56 by a suitable form of stoker, as shown at 57. The stoker 57 is provided with means, as distributor 58 and pressure fluid distributor head 59, for scattering fuel over 25 the fire in aerial paths.

Cinders and unconsumed fuel particles are discharged from the smokebox in the manner described in connection with the preferred embodiment of the invention and delivered to the 30 settling chamber 52 through the conduit 60. The carrier fluid passes through the screen 61 and is vented through the pipe 62, and the solid particles retained by the screen 61 drop by gravity into the pulverizer 63. The pulverized material 35 is ejected into the firebox through the firing opening 56 beneath the distributor plate 58 by the action of the fan 64. The conduit system for the pulverized material includes a nipple 65 formed with the fan casing, a discharge nozzle 40 66, which is preferably formed as an integral part of the stoker discharge casing 67, though obviously it may constitute a separate unit, and an elbow 68 connecting the nipple 65 with the discharge nozzle 66. The pulverized material 45 discharged from the nozzle 66 is burned in suspension in the firebox directly beneath the blanket of fuel being discharged by the stoker. Not only does the proximity, in the firebox, of the burning fine fuel with the fuel discharged 50 by the stoker cause a considerable quantity of fines delivered by the latter to be consumed before escaping over the firebox arch, but also the larger lumps of fuel are preheated and moisture driven off before they reach the firebed. 55

The pulverizing unit and stoker are operated from a common prime mover, as by the turbine 69, thereby coordinating the rate of delivery of the pulverizing unit and the stoker, or in other words, they operate in timed relation. Suitable 60 reduction gearing 70 is provided whereby the stoker may be operated at a slower speed than the pulverizing unit, however, their relative rates will remain constant. Thus, when the stoker is delivering relatively large quantities of fuel to 65 the fire, relatively greater quantities of cinders and unconsumed fuel particles are discharged into the smokebox, and since the stoker and pulverizing unit operate in timed relation, the latter will operate more rapidly to take care of 70 the increased amount of cinders and fuel particles.

I claim:

1. The combination in a locomotive, of a firebox, a smokebox arranged to receive the products 75

of combustion from said firebox, means in said smokebox for separating solid material from the gaseous products of combustion, a conduit extending rearwardly from said smokebox towards the firebox, a pressure fluid blast nozzle arranged to project said solid material through said conduit, means adjacent the forward end of said firebox arranged to receive said solid material and separate it from the carrier fluid, means for pulverizing said separated solid material, and means for projecting the pulverized solid material into the firebox.

2. The combination in a locomotive, of a firebox, a smokebox arranged to receive the products of combustion from said firebox, means in said smokebox for separating solid material from gaseous products of combustion, a conduit system for conveying said solid material extending rearwardly from said smokebox and opening into said firebox, a casing interposed in said conduit system, a pressure fluid blast nozzle arranged to project said solid material to said casing, means in said casing for separating said solid material from the carrier fluid, means for venting the carrier fluid, a pulverizer arranged to receive the solid material from said casing and means for projecting the pulverized solid material into said firebox.

3. The combination in a locomotive, of a firebox having a front water leg with an opening therethrough, a smokebox arranged to receive the products of combustion from said firebox, means in said smokebox for separating solid material from gaseous products of combustion, a conduit extending rearwardly from said smokebox, blast means arranged to discharge said separated material from the smokebox through said conduit, means including a casing adjacent said front water leg communicating with the discharge end of said conduit for separating the solid material from the carrier fluid, a pulverizer for reducing said separated material, a discharge conduit and a fan arranged to project said pulverized material through said opening into the firebox.

4. The combination in a locomotive, of a firebox having a backhead with a firing opening therethrough, a smokebox arranged to receive the products of combustion from said firebox, means in said smokebox for separating solid material from gaseous products of combustion, a conduit system extending from said smokebox to the lower portion of said firing opening for returning said solid material to the firebox, a pressure fluid blast nozzle arranged to project said solid material through said conduit, means interposed between the ends of said conduit system arranged to receive and separate said solid material from the carrier fluid, means for pulverizing said separated solid material and means for projecting the pulverized solid material through said firing opening.

5. The combination in a locomotive, of a firebox having a backhead with a firing opening therethrough, a cab deck extending rearwardly from said backhead, a smokebox arranged to receive the products of combustion from said firebox, means in said smokebox for separating solid material from gaseous products of combustion, a conduit extending rearwardly from said smokebox, a pressure fluid blast nozzle arranged to project said solid material through said conduit, means rearward of said backhead and below the cab deck arranged to receive and separate said

solid material from the carrier fluid, means for pulverizing said separated solid material, and means for projecting the pulverized solid material through said firing opening.

6. The combination in a locomotive, of a firebox having a backhead with a firing opening therethrough, a cab deck extending rearwardly from said backhead, stoker mechanism including a riser conduit delivering solid fuel to and projecting the same into the firebox through said firing opening, a smokebox arranged to receive the products of combustion from said firebox, means in said smokebox for separating solid material from gaseous products of combustion, a conduit extending rearwardly from said smokebox, a pressure fluid blast nozzle arranged to project said solid material through said conduit, means rearward of said backhead and below the cab deck arranged to receive the solid material from said conduit and separate the solid material from the carrier fluid, means for pulverizing said separated solid material, and means for projecting the pulverized material into the firing opening beneath the stream of stoker fired fuel.

7. The combination in a locomotive, of a firebox having a firing opening, stoker mechanism delivering solid fuel to said firebox through said firing opening, a smokebox arranged to receive the products of combustion from said firebox, means in said smokebox for separating solid material from gaseous products of combustion, a conveying system for said separated solid material extending rearwardly from said smokebox through said firing opening, means in said conveying system for pulverizing said separated solid material and means for projecting said pulverized material forwardly in said firebox beneath the stream of stoker fired fuel.

8. The combination in a locomotive, of a firebox having a backhead with a ring opening therethrough, stoker mechanism delivering solid fuel to and projecting the same into the firebox through said firing opening, a smokebox arranged to receive the products of combustion from said firebox, means in said smokebox for separating solid material from gaseous products of combustion, a conveying system for said separated solid material extending rearwardly from said smokebox and delivering into the firing opening beneath the stream of stoker fired fuel, said conveying system including means for pulverizing said separated solid material.

9. The combination in a locomotive provided with a stoker, of a firebox, a smokebox arranged to receive the products of combustion from said firebox, means in said smokebox for separating solid material from the gaseous products of combustion, a conduit extending rearwardly from said smokebox towards the firebox, a pressure fluid blast nozzle arranged to project said solid material through said conduit, means adjacent the forward end of said firebox arranged to receive said solid material and separate it from the carrier fluid, means for pulverizing said separated material, means for projecting the pulverized material into the firebox and means for operating said stoker, pulverizer and material projecting means in timed relation.

10. The combination in a locomotive provided with a stoker, of a firebox, a smokebox arranged to receive the products of combustion from said firebox, means in said smokebox for separating solid material from the gaseous products of combustion, a conduit extending rearwardly from

said smokebox towards the firebox, a pressure fluid blast nozzle arranged to project said solid material through said conduit, means adjacent the forward end of said firebox arranged to receive said solid material and separate it from the carrier fluid, means for pulverizing said separated material, means for projecting the pulverized material into the firebox and a common source of power for operating said stoker, pulverizer and material projecting means in timed relation.

11. The combination in a locomotive, of a firebox having a grate and a backhead with a firing opening therethrough, stoker mechanism delivering solid fuel to and projecting the same into the firebox through said firing opening, a smokebox arranged to receive the products of combustion from said firebox, means in said smokebox for separating solid material from gaseous products of combustion, and a conveying system for said separated solid material extending rearwardly from said smokebox and delivering through an opening in said backhead beneath the stream of stoker fired fuel and above the level of said grate.

12. The method of firing a furnace having a

combustion chamber comprising projecting solid fuel in aerial paths into the combustion chamber and burning it in a firebed supported on the furnace grate, separating solid particles from the effluent gaseous products of combustion, re-introducing the separated particles into the combustion chamber in aerial paths immediately beneath the aerial paths of the main supply of fuel and in the direction of projection thereof and above the firebed in the combustion chamber and burning it in suspension.

13. The method of firing a furnace having a combustion chamber comprising projecting solid fuel in aerial paths into the combustion chamber and burning it in a firebed supported on the furnace grate, separating solid particles from the effluent gaseous products of combustion, pulverizing the separated particles, re-introducing the separated pulverized particles into the combustion chamber in aerial paths immediately beneath the aerial paths of the main supply of fuel and in the direction of projection thereof and above the firebed in the combustion chamber and burning it in suspension.

PAUL A. KETCHPEL. 25
